UNITED STATES PATENT OFFICE.

GEORGE B. LOUDERBACK, OF COMPTON, CALIFORNIA.

WELL TOOL.

Application filed June 24, 1924. Serial No. 722,174.

To all whom it may concern:

Be it known that I, George B. Louderback, a citizen of the United States, residing at Compton, in the county of Los Angeles and State of California, have invented a new and useful Well Tool, of which a specification is set forth below.

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

My invention relates to tools for rotary drilling operations, and particularly to tools having integral means for advancing the cutting blades as they become worn. Among the salient objects of my invention are; first, to provide means for advancing the blades of such a tool while it is at the bottom of a drill hole, by alternately raising and lowering the tool; and, second, to accomplish the above in a simple and rugged construction that may be depended upon to function as intended.

My objects are attained in the manner illustrated in the accompanying drawing, in which—

Figure 1 is a longitudinal central section of the complete tool;

Figure 2 is a similar section taken on a plane perpendicular to that of Figure 1; and

Figures 3, 4, 5, and 6 respectively are enlarged cross sections of the tool taken on the planes 3—3, 4—4, etc., of Figures 1 and 2.

Similar reference numerals refer to similar parts throughout the several views.

In applications for United States patents filed by me on January 16, 1924, Serial # 686,569; February 11, 1924, Serial # 691,998; and May 12, 1924, Serial # 712,735; I have disclosed a novel type and arrangement of cutting blades for a drilling bit, and means for advancing them from the lower end of the tool obliquely to the axis. For convenience of illustration I have taken a somewhat similar tool for disclosing the present invention which, however, differs from all the others in its feeding mechanism, and only the latter is claimed herein. This

feeding mechanism, constituting the present invention, is well adapted for use in a large variety of tools of the general character mentioned above, and for other devices requiring periodic feeding of the cutting blades.

The lower portion of the tool selected for illustration comprises identically shaped halves 7 and 8 having accurately machined or ground faces, assembled face to face so as to contact closely and form a tight joint. The assembling of these body halves is accomplished by means of a wedge ring 9 at the bottom; a tubular housing 10 screwed upon them at an intermediate point; and a screw collar 11 at the top. A pair of through bolts 12 are also used at the bottom.

The body halves are so shaped that, when assembled, the lower portion of the tool is slightly wedge-shaped as indicated in Figure 2. This portion of the body in reality is a modified ellipse in section, as shown in Figure 6, and the section becomes increasingly elongated in its proportions toward the bottom of the tool. In assembling the halves the wedge band 9 is driven up from the bottom onto a slightly tapered seat to a shoulder at 13, and the band is prevented from backing off by means of a pair of wedges 14, shown only in Figure 6. These wedges are driven up from the bottom, under the band, and serve to tighten the latter still further. They may be prevented from becoming displaced in various ways that will occur to those familiar with this class of construction.

The abutting faces of the body halves are variously recessed to form enclosing chambers for the working mechanism when the halves are assembled, and with grooves or channels for guiding the moving parts. The tool illustrated has a pair of oblique bifurcated cutting blades 15 and 16, cross flanged at their upper ends to engage the cross-grooved blade-head 17, to be longitudinally positioned thereby. The blades and blade-head work within shallow rectangular recesses as 18. Furthermore the blades are provided with longitudinal flanges 19, on 100 their leading faces, and these, by engaging corresponding oblique grooves 20 in the body halves, serve to maintain the blades in oblique relation to the axis of the tool. As blade-head 17 is moved downward, the 110 blades are fed obliquely from the end of the tool; their upper ends meanwhile trav-

erse the blade-head in engagement with its cross grooves.

The feeding mechanism which is the subject matter of the present invention, comprises a feed screw 21 engaged by a cylindrical flanged nut 22. The screw is affixed to, or made integral with, the blade-head and does not turn, but the nut may be rotated about its axis to lower the screw and blade-head. The intermediate periphery of the nut is provided with ratchet teeth 23 and a spring ratchet 24 attached within body 7 is adapted to engage these teeth to prevent rotation in a reverse direction. The nut also has a pair of longitudinal splines 25, engaging a driving sleeve 26, by means of which it is rotated. Collars 27 permit the nut to rotate within the body but prevent longitudinal movement and resist the thrust of the feed screw.

The driving sleeve 26 has a transverse radial-ratchet face at its lower end adapted to be engaged by a similar face at the upper end of the cylindrical cam-follower 28. This ratchet engagement is indicated at 29 and ratcheting is accomplished with the cooperation of spring 30, the sleeve being free to slide up and down while in engagement with nut 22 through splines 25.

The feed mechanism is actuated by means of a pair of longitudinal plunger rods 31, normally projecting from the lower end of the tool and terminating in a shoe 32 at the bottom. The upper ends of these rods are attached to a cylindrical driving cam 33 having a multiple thread or helix of relatively great pitch upon its periphery. This thread or helix engages the correspondingly formed interior of cam-follower 28. The driving cam does not rotate, being prevented from doing so by keys 34 adapted to slide longitudinally in engagement with corresponding grooves in the body parts as indicated in Figure 5. Longitudinal movement of the cam serves to rotate follower 28, and thereby to drive feed nut 22 in one direction only, since the nut is prevented from reversing its direction of rotation by ratchet 23. A strong helical spring 35 normally forces cam 33 and the plunger rods 31 downward.

As indicated in the drawings the parts are so designed that when the plunger rods are moved upward by allowing the tool to come down upon the bottom of the drill hole, the driving cam turns follower 28 backward or counter-clockwise, as seen from below. Subsequently, when the tool is lifted, spring 35 forces the cam downward and in so doing the follower is turned clockwise as viewed from the bottom. This results in turning the feed nut in the same direction and lowers the feed screw to advance the cutting blades.

The other features of the construction shown in the drawings have been fully described in the applications above referred to

and are not included within the scope of the present invention. When drilling, the cutting blades are, of course, advanced to occupy positions corresponding to dotted lines 36 in Figure 1. At that time the weight 70 of the tool and tool string is largely, if not entirely, upon the cutting blades, and operating shoe 31 is forced up into recess 37 and does not interfere with the drilling in any way. A circulating passage is provided from 76 end to end of the tool. This comprises the inlet tube 38, distributing head 39, branch pipes 40, and body grooves 41. At the bottom these grooves branch into a pair of diverging passages 42, discharging in front 80 of the forward edges of the cutting blades.

My invention obviously is adapted for use in a large variety of tools including various types of drills, reamers, and such devices as require to have their cutting edges advanced 85 from time to time as the work proceeds.

I claim:

1. A well tool comprising; a tool body; cutting blades adapted for being advanced from said body; longitudinally slideable 90 plunger rods normally projecting from the end of the body, adapted for retraction by the weight of the tool; and mechanism operatively connecting said rods and blades through an interposed cylindrical cam and a ratchet, whereby the blades may be advanced by the reciprocation of the rods.

2. A well tool comprising; a tool body; cutting blades adapted for being advanced from said body; longitudinally slideable 100 plunger rods normally projecting from the end of the body, adapted for retraction by the weight of the tool; and mechanism operatively connecting said rods and blades through an interposed cylindrical cam, a 105 ratchet, and a feed nut adapted for rotation in one direction only, whereby the blades may be advanced by the reciprocation of the rods.

3. A well tool comprising; a tool body; cutting blades adapted for being advanced from said body; longitudinally slideable 110 plunger rods spring constrained to normally project from the end of the body, adapted for retraction by the weight of the tool; and mechanism operatively connecting said rods and blades through an interposed cylindrical cam, a ratchet, and a feed nut adapted for rotation in one direction only, whereby the 115 blades may be advanced by the reciprocation of the rods.

4. A well tool comprising; a tool body; cutting blades adapted for being advanced from said body; longitudinally slideable 120 plunger rods, spring constrained to normally project from the end of the body, adapted for retraction by the weight of the tool; a non-rotating screw having a nut thereon adapted for rotation in one direction only, whereby 125 said blades may be advanced; and

- mechanism operatively connecting said rods and nut through an interposed cylindrical cam and a ratchet, whereby the nut may be turned by the reciprocation of the rods.
5. A well tool comprising; a tool body; cutting blades adapted for being advanced from said body; longitudinally slidable plunger rods, spring constrained to normally project from the end of the body, and adapted for retraction by the weight of the tool; a non-rotating screw having a nut thereon adapted for rotation in one direction only, whereby said blades may be advanced; and mechanism operatively connecting said rods and nut through an interposed helically grooved cam and follower, whereby the nut may be turned in its one operating direction by the reciprocation of the rods.
10. A well tool comprising; movable cutting blades having a non-rotatable feed screw operatively connected therewith; a feed nut upon said screw adapted for rotation by a ratchet in one direction only; and plunger rods normally projecting from the end of said tool adapted to rotate said ratchet by means of an interposed cylindrical cam.
15. A well tool comprising; movable cutting blades having a non-rotatable feed screw operatively connected therewith; a feed nut upon said screw adapted for rotation by a ratchet in one direction only; and plunger rods spring constrained to normally project from the end of said tool adapted to rotate said ratchet by means of an interposed helically grooved cam.
6. A well tool comprising; movable cut-
